TIE PRESS

Filed March 18, 1922

UNITED STATES PATENT OFFICE.

CLARENCE K. CHAMBERLAIN, OF CHICAGO, ILLINOIS.

TIE PRESS.

Application filed March 18, 1922. Serial No. 544,837.

My invention relates to the pressing and smoothing of articles of apparel so that they will be kept substantially in normal shape and condition and free from disfiguring wrinkles. It has special application to the care and preservation of cravats and neckties. The severe treatment to which these articles are subjected usually causes them to be discarded long before their normal usefulness is ended. This is particularly true with ties of the four-in-hand type. It is quite a practice when tying such a scarf to use it as a "cinch" to draw the collar closely into place. Wrinkles are thus produced in the short spaces at which the knot is tied, which are lengthwise of the tie and which, when once started, follow the same general lines each time the scarf is tied. If not pressed out and kept pressed out they rapidly destroy the fabric by establishing lines of wear. It is a further fact that when pressed as usual by the use of a moistened folder and a hot iron the combination of heat and moisture deteriorates the silk, rapidly destroying its quality and lustre.

It is one object of my invention to provide a simple, effective and inexpensive device for removing the wrinkles from scarfs and ties and similar small articles without the use of heat and usually without the application of moisture, leaving the surface in a smooth and pressed condition.

It is a further object of my invention to treat longitudinal wrinkles by the progressively transverse action of clamping faces, the fabric being thus permitted to extend itself freely in advance of the final pressure applied thereto.

Referring to the drawings forming a part of the specification: Fig. 1 shows a perspective view of a device embodying the principles of my invention. Fig. 2 is a section of the same on the line 2—2 of Fig. 10. Fig. 3 shows an end view as opened to receive a tie. Figs. 4 and 5 are details of the hinge construction. Fig. 6 is a finishing piece. Fig. 7 shows the locking device just prior to final closing. Fig. 8 shows an end view of the jaws as closed. Fig. 9 shows the method of unlocking and opening the jaws. Fig. 10 is a plan view showing the device closed and a tie therein under pressure.

Further describing my invention with ref-

erence to the drawings in which like characters of reference denote like parts throughout:

It consists essentially of two members or jaws, 1 and 2 of resilient sheet material such as spring brass, steel or nickel silver or celluloid. Said jaws are curved from side to side forming convex, co-acting faces 1' and 2' adapted to bear on and press the material placed between them as hereinafter explained.

The said jaws or pressing members are hinged together at adjacent straight edges in any suitable or convenient way, but I prefer to accomplish this by means of the structure shown, in which the edge of the inner jaw 2 is given a substantially complete roll forming a tube 4. The corresponding edge of the lower jaw 1 is given a partial roll 5, the latter being so closely formed as to exert slight spring pressure on the inner tube and provide a close fitting and smooth acting hinge. When the jaws are turned relatively to each other as shown in Fig. 3, for the introduction of the article to be pressed, the outer face of jaw 2 in a line adjacent to the hinge will contact with the edge 6 of the outer roll, which forms a stop to limit further opening of the jaws.

The free edges of the jaws may be so formed relatively to each other that a positive and rigid locking device is provided. In doing this I turn the free edge of the lower jaw 1 upwardly on the side of the inner or convex face to form a flange 10 at approximately a right angle thereto and form an inwardly facing bead 11 on the edge of said flange. This bead preferably should consist of a double thickness of the material folded closely on itself and should leave a space or recess 12 therebelow. A similar but narrow flange 13 is formed on the free edge of the upper jaw 2 on the outer or concave side thereof. Said last named flange should be rounded or should be at such an angle to the body of the upper jaw, as to provide a slanting face 14; while a reinforcing bead 15 should be formed by turning the extreme edge of the flange backwardly and folding it upon itself. The width of the two jaws and the flanges and beads thereon should be in such relation to each other that when the device is being closed the slanted face 14 of jaw 2 should strike

against the bead 11 on the flange 10 of jaw 1. Pressure applied in completely closing the jaws will cause the flange 10 to yield outwardly thus permitting the flange 13 on the 5 edge of jaw 1 to pass the bead 11 and set itself in the space 12 therebelow. The flange will spring back to normal position and the jaws will be positively locked together.

It will be seen that when the jaws are given 10 equal initial curvature and have equal spring resistance the curves will be straightened into the relative positions forming a substantial plane as shown in Fig. 8 in which the lock as described is illustrated. It will further be 15 noted that when a tie is being pressed between the jaws in the act of closing; first, the pressure will be uniformly and progressively applied to the fabric, thus pushing out the longitudinal wrinkles ahead of the points of contact of the pressing faces; second, the mutual pressure of the two jaws toward each other will always be equal and the relative positions of the free edges and of the locking devices thereon will always be the same; third, 20 that the lock when formed will be firmly held as long as the jaws remain in their normally relative positions. But when it is desired to release the edges and open the device to remove the tie the device as a whole should 25 be given a backward curve as shown in Fig. 9 thus relatively lengthening the arc of the lower jaw, and shortening the arc of the upper jaw. The free edge of the latter is thus withdrawn from engagement with the overhanging bead of the lower jaw; the lock will 30 be broken, the spring jaws will open automatically and the tie will be released.

It will be observed that as shown the hinge is so formed on the two corresponding edges 40 of the jaws that it is wholly above the plane of contact of the co-acting faces and that in like manner the flanges on the free edges of the jaws provide securing means which are also above the said contact plane. A level 45 underface is thus provided free from projections which might disfigure furniture, while the raised hinge and flange on opposite edges of the device provide convenient means for giving the backward curve to unlock the 50 jaws.

I have described my invention as one in which all elements of an operative structure are integrally comprehended in the two clamping jaws. As a finish, however, for the 55 ends of the hinge I prefer to provide a tubular rivet or eyelet having the barrel 17 of such diameter as to fit snugly within the tubular roll of the inner jaw, and having a flange 18 of width corresponding to the combined widths 60 of the said tubular roll and the external enclosing roll 5. Said finishing eyelets thus further form stops to prevent relatively longitudinal displacement of the rolls forming the hinge structure. Furthermore, when 65 of accurately predetermined diameter the

rigidly tubular barrels of the finishing pieces provide a standard to which slight variations of the hinge rolls will conform.

I claim:

1. A tie press consisting of a pair of oppositely out-curved spring plates having means along one longitudinal edge thereof forming a hinge and having means along the other longitudinal edge thereof forming a clasp to hold the plates in face to face contact, the 75 said clasp forming portions of the plates having limited engagement and being releasable by simultaneous flexure of the plates in one direction.

2. In a tie press, a pair of resilient clamping 80 plates connected with one another along one longitudinal edge and diverging toward their opposite free edges, and contacting gradually from their connected edges toward their outer edges when brought together for transversely 85 stretching the tie, and means along the free edges of said plates having limited engagement forming a clasp adapted to be released by a flexure of said plates in union in one direction.

3. In a tie press, a pair of resilient clamping 90 plates in connection with one another along one edge and diverging toward their opposite free edges, and flanges along the free edges of said plates having beads, the 95 flanges being formed to abut and the beads engaging one beneath the other to form a clasp whose engagement is limited whereby a flexure of the plates in unison in one direction serves to release the clasp.

4. In a tie press, a pair of resilient clamping 100 members in connection with one another at one side of the press and diverging toward the opposite side thereof, said members having engaging portions along the other side 105 of the press, forming a clasp, said engaging portions being disengageable by a flexure of said members in unison in one direction.

5. In a tie press, a pair of outwardly curved 110 resilient plates hinged together along one longitudinal edge and gradually contacting from substantially the hinge connection to the forward edge when brought together and thereby pinching the longitudinal edge of a tie near the hinge and transversely stretching out the creases and means at the forward longitudinal edge of said plates for latching the same together.

6. In a tie press, a pair of outwardly curved 115 and diverging resilient plates each having a rolled head at one longitudinal edge forming a hinge joint whereby said plates gradually come into contacting relation from substantially the hinge joint to the forward longitudinal edge when brought together, said plates pinching a longitudinal edge of the tie near the hinge and transversely uncreasing the tie when brought together and means on the forward longitudinal edge of the plates 120 for securing said plates in closed position.

7. In a tie press, a pair of outwardly diverging and curved resilient plates hinged together at one longitudinal edge for gradual contacting relation from a point adjacent the hinge joint to the forward edge when brought together for pinching a longitudinal edge of a tie near the hinge and transversely uncreas-

ing the same, said plates having interlocking parts at their forward edges for securing the same in closed position.

In witness whereof I have hereunto set my hand at Chicago, Illinois, this 16th day of March, 1922.

CLARENCE K. CHAMBERLAIN.
